UNITED STATES PATENT OFFICE.

WILSON HOWE AND GEORGE H. MINER, OF CHICAGO, ILLINOIS.

APPARATUS FOR CARBURETING AIR.

■ SPECIFICATION forming part of Letters Patent No. 236,159, dated January 4, 1881.
Application filed May 19, 1880. (No model.)

To all whom it may concern:

Be it known that we, WILSON HOWE and GEORGE H. MINER, both of Chicago, in the State of Illinois, have invented a new and useful Improvement in Apparatus for Carbureting Air for Illuminating Purposes, of which the following is a specification.

Our invention relates to the form, construction, and arrangement of the several parts constituting the apparatus.

We are aware that a great number of machines or apparatus for carbureting air for illuminating purposes have been patented, and that many of them have been made and put in use, producing results more or less satisfactory, all based upon the general feature of forcing air through a chamber containing gasoline or other similar hydrocarbon fluid. The difficulty to which most, if not all, such machines heretofore made have been subject, and which our improvements overcome, is the great want of uniformity in the burning and illuminating qualities of the carbureted air, or "gas," as it is generally termed, it being at times much more fully charged with the vapor of the gasoline than at other times, as when a machine or carbureting apparatus is newly or fully charged with gasoline the air driven through the machine takes up a much greater quantity of vapor from the gasoline than it will when the apparatus has been running for some time after it has been charged and the gasoline is partially or nearly exhausted, producing in one case a strong illuminating-flame and in the other a flame of much weaker illuminating power.

In the use of our improved apparatus the carbureted air, as it passes from the carbureting apparatus, is at all times equally and uniformly charged with the vapor of the gasoline, and consequently the combustion at the burner is at all times the same, and a uniform light is always produced.

As in all the other carbureting-machines referred to, we force air through a chamber charged with gasoline or its equivalent. This may be done by any of the well-known devices for that purpose; but where it is practicable to use a flow of water having a considerable fall we prefer the use of it in the arrangement shown in Fig. 2 of the drawings.

The carbureting-chamber we prefer to make in the form of an upright cylinder, its dimensions corresponding to the number of burners to be supplied with carbureted air.

In the drawings annexed, Figure 1 shows a vertical section of a reservoir of gasoline, from which the carbureting-chamber is supplied by natural flow, and its connections with the carbureting-chamber. Fig. 2 shows a vertical section of a form of apparatus for forcing air through the carbureting-chamber by the flow of a small stream of water under a considerable head. Fig. 3 shows a vertical sectional view of the carbureting-chamber, in partial perspective, with its internal apparatus and connections with the reservoir of gasoline and the air-forcing apparatus. Fig. 4 shows a plan of the bottom of the carbureting-chamber, with the air-induction pipe and its distributing branches lying upon it. Fig. 5 shows a plan of the distributing-plate upon which the gasoline is intermittently discharged, and through the perforations of which it is evenly distributed over the whole diameter of the carbureting-chamber. Fig. 6 is a vertical section, at right angles to the section represented by Fig. 3, through the carbureting-cylinder, showing distinctly the studs supporting the weighted side of the tilting pans and the supplementary chambers e^2 .

The letters used in the drawings designate the same parts in all the several different figures in which they appear.

a is the air-induction pipe, extending from the forcing apparatus through the top of the carbureting-chamber to and across the lower floor of the carbureting-chamber.

a' a' are branches from the pipe a , taken out at short spaces on both sides of it, and extending from it to the wall of the carbureting-chamber, and are perforated on the sides with fine holes to distribute the air forced through the pipe a uniformly through the whole area of the floor of the chamber.

a^2 is a pipe from the open space between the two floors of the carbureting-chamber, carried up above the second floor of the chamber high enough to prevent the gasoline on the second floor from flowing down it, then turning downward to and lying across the second floor as the pipe a lies on the lower floor, having the

perforated branches a' arranged as on the lower floor.

a^3 is the eduction-pipe through which the carbureted air passes to the burners.

5 c is a pipe which conducts the gasoline from the reservoir, Fig. 1, to and into the tilting pan in the upper part of the carbureting-chamber.

c' is a cock in the pipe c , which is opened 10 and closed, as the service of the apparatus requires, by the movement of the lever c^2 .

c^2 is a simple lever pivoted and connecting the cock c' with the movable connecting-rod c^3 , which extends downward through c^4 , a sleeve 15 or tube, and connects with c^5 , a float in c^6 , a chamber on the lower floor of the carbureting-chamber, having openings at the bottom to allow it to fill with gasoline from the carbureting-chamber.

20 e is a tilting pan of oval form, having on one side a weight and on the other side a small supplementary pan, the whole suspended by a rod passing through the longer diameter of the pan and resting at its ends upon supports 25 fixed to the wall of the carbureting-chamber.

e' is the weight upon a stud fixed on the wall of the chamber, supporting the pan in a horizontal position. e^2 is the weight mentioned. e^2 is the small supplementary pan mentioned 30 on the side of the pan e , into which gasoline will flow from the pan e when it is filled up to the opening into e^2 .

e^3 is the rod upon which the pan e is suspended, passing through the pan in the line of 35 its longest diameter, a little one side of its center line, and resting at its ends in bearings on the wall of the carbureting-chamber loosely, so that it will revolve partially and allow the pan e to tilt over and discharge its contents.

40 g is the water-passage through which a current flows into the air-forcing apparatus, (shown in Fig. 2,) having a nozzle or delivery contracted to a diameter much smaller than that of the water-pipe, discharging the flow of 45 water through the center of a pipe of larger diameter below, into which, through the opening marked g' , air is drawn by the flow of water and forced into g^2 , an air-chamber, having g^3 , a partition cutting off a part of one side of 50 the air-chamber g^2 , with openings only at the bottom of the partition, through which the water passes to g^4 , an opening, through which it escapes.

h is a bed of absorbent material, preferably 55 coarse sawdust. Two of these beds are shown in the drawings, one above the other.

i is a second floor of the carbureting-chamber, about eighteen inches above the first or lower floor, supporting the air-pipe a^2 and its 60 distributing-branches and a second bed of absorbent material.

k is a circular metallic plate, of diameter equal to the inside diameter of the carbureting-chamber, thickly perforated with fine holes 65 and resting over the bed of absorbent material, and upon which the gasoline flows, and, fall-

ing through the perforations, is evenly distributed over the absorbent bed below. There are two shown.

m is a pipe through which the gasoline, 70 when it has risen on the second floor of the carbureter to the height of about six inches, will flow into the pan e below, its lower end being sealed, so that air cannot pass up through it, by carrying it down below the lower pan e a 75 distance a little greater than the height of the bend of the air-pipe a^2 above the second floor, and then turning it up and carrying its discharge-opening over the edge of the lower pan e in such manner as not to interfere with its 80 tilting.

The object of the second flooring in the carbureting-chamber, the second set of air-distributing pipes, bed of absorbent, and perforated plate is to increase the carbureting power 85 of the apparatus, so as to allow the air to be forced through it with much greater rapidity, and thus supply twice as many burners as could be supplied if only one floor were used. Where but few burners are to be supplied one 90 floor is sufficient.

It is obvious that more than two floors may be placed in one carbureting-chamber by increasing its height, and where a large number of burners are to be supplied three or four 95 floors may be used.

The machine being constructed and set in its place, with all its connections made and the reservoirs for gasoline filled, the cock in the pipe c is opened and the gasoline flows into 100 the upper pan e until it is filled nearly full, when it flows into and fills the small supplementary pan e^2 , the weight of which, when filled, will overbalance the weight e' on the other side of the pan e and tilt it a little, when the 105 body of the gasoline, filling the pan, flows toward the declining side, and the increased weight tilts the pan far enough over to empty its entire contents upon the perforated plate k , spreading the fluid over its entire surface. 110 As soon as the gasoline has gone out of the pan e the weight e' instantly brings it back to its position, and it is again filled and again emptied, and so on until the upper bed of absorbent is saturated and the gasoline fills the 115 floor deep enough to flow through the pipe m . The filling and emptying will continue until the lower bed of absorbent is saturated and the lower floor of the carbureting-chamber filled with the gasoline to the depth of six or eight 120 inches. The gasoline flowing into the small chamber c^5 raises the float c^6 and rod c^3 , moving the lever c^2 , closing the cock c' . At this point of progress the air-forcing apparatus is set in motion, and air is driven through the 125 pipe a to and across the lower floor of the chamber, issuing from the holes in the branch pipes a' , is evenly distributed, and rises through the whole body of gasoline on the lower floor of the chamber and through the body of absorbent material and the perforated plate k into 130 the open space where the lower pan e is sus-

pended; thence it enters the air-pipe a^2 and its distributing-branches, rising through the second stratum of gasoline and absorbent material and perforated plate, fills the open space, and passes to the burners through the pipe a^3 . When the passage of air through the lower stratum of gasoline has taken up enough of it to lower the float c^6 two or three inches, its descent, acting on the lever c^2 , opens the cock c' , and the upper pan e fills and empties until the float rises again and closes the cock c' .

It is obvious that the air forced through this carbureting-chamber will always be equally and uniformly charged with gasoline vapor while the gasoline-reservoir is kept supplied.

The apparatus may be located in a pit or small brick or stone structure at some distance away from the building to be lighted.

We claim as new and our invention—

1. In a chamber for carbureting air for illuminating purposes, the tilting pan e , having on one side of it a weight, which rests on a stud in the wall of the chamber, and on the other side of it a small supplementary chamber, and

supported by a rod passing through its longer diameter on one side of its center line, all substantially as described, and for the purpose specified.

2. In a carbureting apparatus having two or more floors and chambers and two or more sets of air-distributing pipes, the bent tubes a^2 and m , in combination with the carbureting-chambers, substantially as described, for the purposes stated.

3. In a chamber for carbureting air, in combination with an air-forcing apparatus, reservoir for gasoline, bed of absorbent material, perforated distributing-plate, the tilting pan e , made as described, and the air-distributing pipe a' , placed on the floor of the chamber below the surface of the gasoline, all made substantially as described, for the purpose specified.
